(57) CLAIM

The ornamental design for a molded play station connector, as shown in the accompanying drawings.

DESCRIPTION

A portion of the disclosure of this design patent application document contains material to which a claim for a copyright is also made. The copyright owner has no objection to the facsimile reproduction of this design patent application by anyone as it appears in the Patent and Trademark Office patent file or records, but reserves all other copyrights whatsoever.

FIG. 1 is a perspective view of a molded play station connector, in accordance with the present invention.

FIG. 2 is a plan view of a molded play station connector, in accordance with the present invention, as depicted in FIG. 1.

FIG. 3 is an underside view of a molded play station connector, in accordance with the present invention, as depicted in FIG. 1.

FIG. 4 is a side view of a molded play station connector, in accordance with the present invention, as depicted in FIG. 1.

FIG. 5 is a corresponding side view of a molded play station connector, in accordance with the present invention, as depicted in FIG. 1, as depicted in FIG. 1.

FIG. 6 is a rear view of a molded play station connector, in accordance with the present invention, as depicted in FIG. 1; and,

FIG. 7 is a frontal view a molded play station connector, in accordance with the present invention, as depicted in FIG. 1.
